UNITED STATES PATENT OFFICE.

EMILE GÉRARD, OF LIMOGES, FRANCE, ASSIGNOR TO HAVILAND & ABBOT,
OF NEW YORK, N. Y.

DESIGN FOR A DISH.

SPECIFICATION forming part of Design No. 21,989, dated November 15, 1892.

Application filed October 4, 1892. Serial No. 447,839. Term of patent 7 years.

To all whom it may concern:

Be it known that I, EMILE GÉRARD, a citizen of the French Republic, residing at Limoges, France, have invented and produced a new and original Design for Dishes, of which the following is a full, clear, and exact description, reference being had to the accompanying drawing, in which the figure shown is a side view of a covered deep dish embodying my design.

This invention relates to a new and original design of the form and configuration of dishes, &c., as hereinafter described and shown.

The principal features of my design are the configuration of the rim of the dish and its cover, the form of the dish itself with its undulating portions, and the handles which it will be observed at one portion appear to come from the body of the article, and another portion of said handle apparently merely rests upon the body.

In the drawing, A represents the body of the dish and cover provided with handles B, which apparently sprout from the body A of the dish or cover itself at one portion, as shown at a, and appears to merely rest upon the body A at another portion, as shown at b. Around the rim of the cover at certain intervals are undulating portions d. The dish has 3, depressions e near the bottom.

Portions of my design present a leaf-like appearance f, apparently overlapping the adjacent parts.

What I claim is—

The design for a dish, substantially as shown described.

EMILE GÉRARD.
